UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,387,251.

Specification of Letters Patent.

Patented Aug. 9, 1921.

Application filed December 16, 1919. Serial No. 345,311.

To all whom it may concern:

Be it known that I, CLARENCE B. FOWLER, a citizen of the United States, residing at New York, in the county of New York, State 5 of New York, have invented certain new and useful Improvements in Telephone Systems, of which the following is a full, clear, concise, and exact description.

This invention relates to telephone systems and has for its object the production 10 of improved signaling means for such systems.

In the present embodiment of this invention means, individual to a subscriber's 15 line, are provided at a central office whereby after restoring his receiver to the switchhook a calling subscriber may, by removing his receiver from the switchhook before the disconnection of the cord circuit from his 20 line, operate a distinctive signal to recall the operator. The operator on noticing the recall signal may discontinue its operation by touching the sleeve contact of the answering plug or jack with the tip of the plug of 25 any cord circuit, as in making a busy test, and may then depress her listening key to connect her head set with the line.

By providing apparatus individual to the 30 subscribers' lines for furnishing a distinctive recall signal, it is unnecessary to install special cord circuits when this feature is desired by lines terminating in an exchange provided with cord circuits not arranged for such recall signals.

Figure 1 of the accompanying drawing is 35 a diagrammatic representation of that portion of a telephone system necessary to an understanding of the invention. There is shown a subscriber's line 1, which terminates at a central office in an answering jack 2, and in multiple jacks 3, of which but one is shown. An answering plug 4 of one cord circuit is shown, but any number of cord 40 circuits may be used. The relays and line lamp shown are individual to the line, and the supervisory lamp to the cord circuit, but the battery and interrupter may be common to several cords and lines. Fig. 2 of the 45 drawing shows diagrammatically the method 50 of discontinuing the recall signal by touching with the tip of an idle plug, the sleeve contact of the plug of a connected cord circuit. It is believed that the invention will be readily understood from a consider-

ation of the operation of the system, which 55 is as follows:

A subscriber desiring to initiate a call removes his receiver from its hook, thereby completing an energizing circuit for line relay 5 which may be traced from grounded 60 battery through the right hand winding of relay 5, back contact and inner armature of cut-off relay 6, and thence through the subscriber's line loop, outer armature and back contact of relay 6, through the left hand 65 winding of relay 5 to ground. Relay 5 in energizing completes a circuit from grounded battery through lamp 7, contact and innermost armature of relay 5, back contact and inner armature of sleeve relay 70 8, to ground. Line lamp 7 is lighted in this circuit to inform the operator that a call has been initiated. The operator thereupon inserts plug 4 of an idle cord circuit in answering jack 2 of the calling line and 75 depresses her listening key 10, to connect her head set (not shown) to the line, and may thereafter complete the connection in the well known manner, the calling end of the cord circuit and the called line not being shown as they form no part of the present invention. Upon the insertion of plug 4 in jack 2, a circuit is completed from grounded battery through lamp 9, sleeve contacts of plug 4, and jack 2, through the 80 right hand low resistance winding of sleeve relay 8 and the left hand high resistance winding of this relay to ground. Relay 8 is energized in this circuit, but is of such high resistance that lamp 9 does not light. 85 In attracting its inner armature relay 8 interrupts the circuit of line lamp 7, to extinguish this lamp. In attracting its outer armature relay 8 connects battery through resistance 11, to the sleeve contacts of the 90 multiple jacks of the calling line in order to furnish a busy test.

At the completion of the conversation when the calling subscriber replaces his receiver on its switchhook he interrupts the 100 previously traced circuit for line relay 5 and this relay becomes inert. A circuit is thereupon completed from grounded battery through the winding of relay 12, back contact and outermost armature of relay 5, front contact and inner armature of relay 8 to ground. Relay 12 in attracting its left hand armature completes a locking circuit 105

for itself independent of the contact of relay 5, and in attracting its right hand armature completes a circuit from ground, back contact and middle armature of relay 5, right hand armature and front contact of relay 12, through the right hand winding of relay 8, sleeve contacts of jack 2 and plug 4, through supervisory lamp 9 to grounded battery. The high resistance winding of relay 8 is shunted by this circuit to light supervisory lamp 9 to furnish a disconnect signal, but relay 8 is held energized.

Should the subscriber desire to recall the operator, after having replaced his receiver on its switchhook, he removes it therefrom and again completes the circuit for the line relay. Relay 5 in attracting its middle armature includes interrupter 13 in the previously traced circuit for the supervisory lamp 9, thereby causing this lamp to flash and notify the operator that her attention is desired. The operator noticing the flashing supervisory lamp gives the call attention and to discontinue the flashing of this lamp touches the sleeve contact of plug 4 with the tip contact of any idle plug, as in making a busy test. Fig. 2 of the drawing shows diagrammatically how this is accomplished. Ground is connected through the upper left-hand winding of the repeating coil, the tip contact of the idle plug, the sleeve contacts of plug 4 and jack 2 to the grounded, serially connected windings of relay 8, thus shunting these windings. Relay 8 in deenergizing opens the locking circuit for relay 12, which deenergizes to open the circuit for the supervisory lamp 9, thus extinguishing this lamp. Upon removing the plug with which she has touched the sleeve of plug 4, the operator breaks the shunt circuit for relay 8 and this relay is again energized through both windings in series with the line lamp and the relays are in the condition in which they normally should be during the progress of a call.

When line 1 is called, battery is connected through the sleeve of the calling plug (not shown) and the sleeve of multiple jack 3, through the outer armature and back contact of relay 8 and the winding of cut-off relay 6 to ground. Relay 6 is en-

ergized in this circuit to cut off line relay 5 which supplies talking current to line 1 when it is a calling line, talking current now being supplied through the calling end 55 of the connected cord circuit.

What is claimed is:

1. In a telephone system the combination with a telephone line, a cord circuit for extending said line, a signaling device individual to said cord circuit, and means individual to said telephone line responsive to an interruption of said line for operating said signaling device in one manner to give a disconnect signal, said means being responsive to a subsequent closure of said line to operate said signaling device in a different manner to give a recall signal.

2. In a telephone system the combination with a telephone line, a cord circuit for extending said line, a signaling device associated with said cord circuit, a set of relays individual to said line operated in response to the closure of said line and the connection of said cord circuit to said line 75 to prepare an operating circuit for said signaling device, a relay operated in response to the interruption of said line for completing said operating circuit, and an interrupter included in said operating circuit, 80 in response to a subsequent closure of said line to operate said signaling device intermittently.

3. In a telephone system the combination with a telephone line terminating in a spring jack, a number of cord circuits for association therewith, signaling devices associated therewith, a line relay responsive to the closure of said telephone line, a second relay individual to said line operated in 90 response to the deenergization of said line relay to complete an operating circuit for one of said signaling devices, and means for causing the release of said second relay by making electrical connection between a contact of an idle plug, and a contact of a plug inserted into the spring jack of said line circuit.

In witness whereof, I hereunto subscribe my name this 6th day of December, A. D. 100
1919.

CLARENCE B. FOWLER.
